UNITED STATES PATENT OFFICE

GLENN MUFFLY, OF RICHMOND, MICHIGAN, ASSIGNOR TO COPELAND PRODUCTS, INC.,
OF DETROIT, MICHIGAN, A CORPORATION OF MICHIGAN

REFRIGERATOR

Application filed February 20, 1930. Serial No. 429,863.

Although broadly entitled, this invention relates to means facilitating the removal of slideable trays from refrigerators of those modern types in which a heat-transfer liquid is employed; and it aims particularly to provide simple and effective means for separating or loosening a tray from a support to which it may have become adherent by reason of the freezing of condensed moisture between said tray and said support.

The specific means employed to impart a preliminary upward movement to a tray or trays may include a lever, a wedge, or a like element; and said element may be either automatically or manually manipulable,—preferred embodiments of the invention being such as include handles additional to those provided for the manipulation of the trays. These additional handles, or parts connected therewith, may be movable through suitable openings provided in a so-called "baffle" plate, or in the respective front plates of the separate trays.

Other objects of the present invention, including the provision of means whereby a set of trays disposed one above another in a usual manner may be simultaneously or successively loosened from their supports by either manual or automatic means, may be best appreciated from the following descriptions of illustrative embodiments of the invention, taken in connection with the appended claims and the accompanying drawings:

35 Figure 1 is a front elevational view of a refrigerator equipped with an embodiment of the present invention,—a door being swung open in such manner as partially to exhibit the same and optional features being included.

40 Figure 2 is an enlarged elevational view (with parts broken away and optional features included) corresponding to an upper left hand portion of Figure 1.

Figure 3 is a vertical sectional view, taken 45 somewhat as suggested by the line 3—3 of Figure 2, but with parts omitted.

Figure 4 is a view corresponding to a central portion of Figure 2, but further enlarged and showing an alternative form.

50 Figure 5 is a vertical sectional view, taken

substantially as indicated by the line 5—5 of Figure 4.

Figure 6 is a vertical sectional view, comparable to Figure 3, but taken substantially as indicated by the line 6—6 of Figure 7 and 55 showing another alternative form.

Figure 7 is a vertical sectional view taken substantially as suggested by the line 7—7 of Figure 6.

Figures 8 and 9 are respectively a partial 60 elevational and a vertical sectional view comparable with Figures 4 and 5, but showing another modified form.

Referring first to the more general features of the invention, as shown in that embodiment thereof which has been selected for illustration in Figures 1—3, inclusive, Figure 1 shows a refrigerator 10 of modern type, any usual machinery being enclosed in a base portion 11, and a food compartment and a 65 tray compartment being respectively provided with doors 12 and 13. Slidable trays, provided with front plates 14 bearing handles 15 may be of a usual or a slightly specialized 70 design, as hereinafter described; and, to overcome the annoying tendency of said trays to stick, after they have been left undisturbed for a period sufficient to permit them to "freeze down", the present invention proposes to employ cam means such as wedges 75 or levers 16, extending below co-operating cam surfaces provided by or on the trays, said levers or wedges being manipulable by handles 17, for separating said trays from their supports.

Before completing a detailed description 80 of that form of the invention shown in Figures 2 and 3 (which includes optional features and complications unnecessary to an understanding of the principles relied upon) 85 attention may advantageously be directed to a simpler embodiment, such as that shown in Figures 4 and 5. In these latter figures, a lever 16a is shown as provided with a handle 17a and as pivoted at 18a upon a fixed element in the form of a bracket 19a. This bracket may be an "angle" carried by a tank or other container 20a for a heat-transfer liquid,—which may be ordinary brine; and a tray 21a, shown as connected with a front 90

plate 14a carrying a handle 15a by an integral extension 22a, may rest upon rounded beads 23a, shown as provided in a wall of the tank 20a. An inwardly extending arm 24a of the lever 16a may be provided with a cam surface 25a, shown as disposed beneath a cam surface on the tray 21a by the described construction; and the handle 17a may project through a slot 26a provided in a so-called baffle plate 27a,—engageable by the respective front plates 14a of the series of trays.

In the embodiments shown in Figures 6 and 7, although an upward cam pressure may be applied substantially centrally of each tray and near the front thereof, instead of providing a substantially central opening beneath each tray and through which an individual lever extends (as at 26a in the form shown in Figures 4 and 5) it is suggested that, to permit of the successive loosening of a series of trays 21b, 21b', 21b'', disposed one above another, means including a master lever 28b may be employed. In this form, integral extensions 22b, 22b', 22b'' are shown as provided with downwardly and inwardly projecting cam surface elements 29b, 29b', 29b''; and the latter are shown as respectively engaged by co-operating cam surfaces 25b, 25b', 25b'', provided upon transversely extending levers 16b, 16b', 16b''. These levers are shown as respectively pivoted at 18b, 18b' and 18b'', in such manner as to permit sequential manipulation thereof upon a depression of the mentioned master lever 28b,—shown as also extending transversely and as pivoted at 31b. In order to transmit motion from said master lever to the respective levers 16b, 16b' and 16b'', use may be made of means such as a slidably element 32b, which may be retained by means such as clips 33b and may be provided not only with series of pins 34b, 34b', 34b'', adapted successively to engage the respective tray-lifting levers 16b, 16b', 16b'', but also with a cam head 35b, disposed suitably for engagement by a co-operating cam surface 36b upon an arm 37b of the lever 28b.

It will be obvious that although the respective tray-lifting levers might be provided with forward extensions to serve as handles for the separate manipulation thereof, the described construction is favorable to the use of the single master lever 28b, or its equivalent, for the manipulation of any desired number of trays,—as by means of a single pry-effecting handle 38b extending through a suitable slot in baffle plate 27b, or its equivalent, and suitable for engagement either by a part (not shown) on door 13 or by a hand; and the spacing of the pins 34b, 34b', 34b'', in the indicated manner is intended to obviate such exertion as would be required simultaneously to separate a plurality of trays from their supports. In case the master lever 28b is unprovided with a spring, retraction

may be effected by gravity means and/or by means such as separate tension springs 39b, 39b', 39b'',—comparable in function with a compression spring as suggested at 39a in Figure 5.

In the simple form shown in Figures 8 and 9, a cam in the form of a wedge 24c is shown as extending beneath a cam surface 29c, directly provided by a tray 21c and manipulable by a handle 17c,—accessible in front of a baffle 27c and/or a front plate 14c. This pry-effecting handle may be connected with a square or other non-circular portion 40c extending through an opening of corresponding outline in a guide 41c. The cam wedge 24c and other slidably parts may be normally held retracted by means such as a spring 39c,—shown as extending between the guide 41c and a pin 41c' upon rod 16c.

Returning now to Figures 2 and 3, these figures incidentally show one of many means for an automatic separation of trays incidentally to the opening of a door 13 beyond a predetermined limit; but these figures also suggest the use of comparatively powerful 85 prying members in the form of "first" class levers 16, 16', 16''. These are shown as pivoted at 18, 18' and 18'' and their respective pivot pins may extend through brackets or bosses 43, 43', 43'', comparable with brackets 95 43a of that embodiment which is shown in Figure 5 and with brackets 43c, 43c', 43c'' of the form shown in Figures 6 and 7.

Numerals being similarly employed as reference characters, but with distinguishing letters, in the descriptions of the various illustrated embodiments of the present invention, it will be seen that handles 17, 17', 17'', provided on or by the mentioned levers, may extend forwardly, in the form shown in Figures 2 and 3, through arcuate slots or other openings 26, 26', 26'', to provide means, accessible in front of baffle 27, for a convenient separate manipulation of said levers. The movement of these levers may, if desired, be limited by means such as clips 44, 44', 44'' (comparable with clips 44b, 44b', 44b'' of that form which is shown in Figures 6 and 7); and said handles may be yieldably held in their upper positions by means such as 115 separate springs 39, 39', 39'',—said clips and springs being secured to brine tank 20 by means such as screws 45 and brackets 46. The brine tank may be secured, in any of the illustrated forms, by means such as upwardly 120 extending straps 47, 47' and laterally extending straps 48; and the so-called baffle plate 27 may be supported from said tank by means such as screws or bolts 50, shown as carrying spacers 51, extending through brackets 125 52.

Although the constructions shown in other figures are economical and effective, a diminution in thermal conductivity from pans 21, 21', 21'' may be effected if desired, by spac- 130

ing the plates 14, 14', 14'' from downwardly deflected portions 53, 53', 53'', of forward extensions 54, 54', 54'',—shown as integral with said pans. For example, use may be made of additional spacers such as that shown at 55'' as surrounding a screw or bolt 56; and this construction is favorable to the support of forwardly extending cam elements 29, 29', 29'' by means including integral flat parts 57, 57', 57'', integral therewith and secured to the downwardly deflected portion 53, 53', 53'' of the respective pans.

The leverage provided by the construction last described may be sufficiently powerful to assure especially easy operation; and it will be evident that this construction also admits of an advantageous use of means, such as a slidable rod or other element 32 carrying spaced pins 34, 34', 34'', for releasing all pans by one movement,—the features here referred to being either additional to or alternative to the separate use of pry-effecting handles 17, 17', 17''. For example, the rod 32, if employed, may be provided with either or both a handle 38, for its manual manipulation, and a lever 58 for its automatic manipulation. This last-named lever is somewhat diagrammatically shown as pivoted at 59 upon a bent bracket 60 and as so connected with a cord or chain, extending to an eyelet 62 upon the door 13, that the opening of said door beyond a predetermined limit tends to depress rod 32 and thereby successively to loosen 21, 21', 21''.

It will be seen that all illustrated forms of this invention include a pry-effecting cam member which is largely or entirely concealed by a so-called baffle plate and is so movable beneath a cam surface provided by or connected with a pan as easily to separate the same from a cooling and/or supporting surface therebelow. The advance of the movable cam may ordinarily be effected by means of a lever so shaped and positioned as normally to remain out of the path of the tray; and the lever may generally be so formed and pivoted below the bottom of the tray that the latter can be freely withdrawn and inserted thereover, the tray itself being unencumbered with any lift-applying or prying cam device including movable parts. Although the use of a cam in the form of a wedge has been suggested, the prying device may more generally include a lever or levers,—one arm of each lever being optionally engageable by pins upon a sliding rod and/or provided with a handle accessibly disposed in front of a baffle plate and distinct from any tray-withdrawing handle. The cam engageable surface of each tray may generally be at or near the level of the entire bottom thereof; but it will be understood not only that various features of the present invention might be independently employed but also that numerous modifications, additional to any suggested herein,

might easily be devised by skilled workers, if informed of the foregoing,—all without departure from the scope of the present invention, as the latter is indicated in the following claims.

1. In loosening means for refrigerator trays, each tray being provided with a downwardly disposed cam surface: a lift-applying device including a cam member disposed for engagement with said cam surface,—said refrigerator including a baffle provided with an opening through which said tray is removable, and said device being provided with manipulating means including a part accessible in front of said baffle.

2. In loosening means for refrigerator trays, each tray being provided with a downwardly disposed cam surface: a lift-applying device including a cam member disposed for engagement with said cam surface,—said refrigerator being provided with a door; and said device being provided with means automatically manipulating the same upon the opening of said door beyond a predetermined limit.

3. In a loosening means for refrigerator trays, each tray being provided with a surface disposed favorably for engagement by a cam, levers disposed out of the path of withdrawal movement of the trays and including cams which are engageable with said surfaces for securing a prying effect, and a common means for operating all of the levers.

4. In a loosening means for refrigerator trays, each tray being provided with a surface disposed favorably for engagement by a cam, levers disposed out of the path of withdrawal movement of the trays, and including cams which are engageable with said surface for securing a prying effect, and a single means for operating the levers in sequential order.

5. A loosening means for refrigerator trays, each tray being provided with a surface disposed favorably for engagement by a cam, levers disposed out of the path of withdrawal movement of the trays and including cams which are engageable with said surfaces for securing a prying effect, and means including a slidable rod for operating all of the levers.

6. In a loosening means for refrigerator trays, each tray being provided with a surface disposed favorably for engagement by a cam, levers disposed out of the path of withdrawal movement of the tray and including cams which are engageable with said surfaces for securing a prying effect, and means including a slidable rod for operating the levers in sequential order.

7. In a refrigerator having a door and ice trays, each tray being provided with a surface disposed favorably for engagement by a cam, levers disposed out of the path of withdrawal movement of the trays and including

cams which are engageable with the surfaces for securing a prying effect, and means operatively connected to the door of the refrigerator for operating the levers upon opening 5 the door beyond a predetermined limit.

8. A loosening means for refrigerator trays, each tray being provided with a surface disposed favorably for engagement by a cam, levers disposed out of the path of 10 withdrawal of movement of the trays including cams which are engageable with said surfaces for securing a prying effect, and resilient means for retracting the levers.

9. In a loosening means for refrigerator 15 trays, each tray being provided with a surface disposed favorably for engagement by a lifting means, and a common means for lifting the trays in sequential order.
